UNITED STATES PATENT OFFICE.

HELEN F. TROWBRIDGE, OF PORT WASHINGTON, NEW YORK.

TOY ANIMAL.

1,023,401.

Specification of Letters Patent. Patented Apr. 16, 1912.

Application filed March 4, 1911. Serial No. 612,184.

To all whom it may concern:

Be it known that I, HELEN F. TROWBRIDGE, a citizen of the United States, residing at Port Washington, Long Island, New York, 5 have invented certain new and useful Improvements in Toy Animals, of which the following is a clear, full, and exact description.

This invention relates to an improvement 10 in toy animals for children, which contains many hygienic and sanitary advantages commanding it to mothers, and which also furnishes an additional interest and amusement to children.

15 This invention may be applied to any of the ordinary animal or doll figures such as Teddy-bears, dogs, cats, etc., and in the present embodiment I have shown it particularly as applied to a lamb.

20 In general this invention consists in forming a stuffed body portion into the figure desired, having an inner cover permanently secured about the same to hold the stuffing in place, while over this inner cover is 25 placed an outer cover constructed to closely fit the stuffed body portion and made of material which will resemble the external appearance of the animal's skin or fur.

I do not wish my invention to be limited 30 however, to the specific form shown herein as it may be embodied in any of the forms broadly defined in the appended claims.

Referring to the drawings, Figure 1 shows the inner stuffed body portion; Fig. 2 is a perspective view of the animal toy 35 with its outside cover in place; Fig. 3 is a detached view of the head portion of the outside cover; and Fig. 4 is a detached perspective view of the body portion of the 40 outside cover.

Referring more particularly to the drawings, 1 indicates the stuffed inner cover preferably of smooth fabric sewed or fastened together about the stuffing in the 45 usual way. An outside removable cover of washable material is detachably secured about the body portion 1 and this outer cover is preferably made of two parts indicated at 2 and 3, the portion 2 of which is 50 designed to envelop the body portion of the animal, and the part 2 to cover the head. The body portion 2 of the outer cover, is 55 preferably separable along its back and provided with detachable fastening devices or hooks 4 to secure the same snugly about the body of the animal. The head portion 3

is likewise slotted along the back portion of the head sufficient to allow the insertion of the animal head therein, and this slit is also provided with fastening devices or 60 hooks 4 for fastening the same together. The head portion 3 of the outer cover should partly overlap the portion 2 adjacent the neck, and the seam between these two portions may be concealed in any suitable way, 65 in the present instance by an ornamental collar 6.

It will be observed that the inner body portion 1 of the toy is quite smooth over its exterior and is not provided with any of 70 the usual appendages of an animal, such as ears, eyes, tail, etc. The outer cover 2 and 3 which is designed to envelop this body portion is, however, provided with the usual appendages of the animal, such as ears 5 75 and tail 5' and eyes 5'', so as to give it a lifelike appearance. The advantages of this arrangement for toy animals is that the outer covering may be washed and replaced whenever desired so that the child may 80 always have a clean, sanitary plaything. Furthermore, the novelty of being able to remove the outer covering of such a toy animal in a similar way to undressing a doll greatly amuses children. 85

When this toy is made up in the form of a lamb, as herein shown, the outer covering may be made of white pile or tufted fabric which resembles very closely that of lamb's wool, and is also washable, without deterioration. 90

What I claim is:

1. A toy animal comprising an inner incomplete body portion free from appendages and designed to give substantial shape 95 to said animal, an outer removable covering of washable material completely inclosing said body portion and having appendages thereon to complete the natural appearance of said animal, said covering provided with 100 detachable devices for being removably secured around said body portion.

2. A toy animal comprising an incomplete body portion free from appendages and designed to give substantial shape to 105 said animal, an outer removable covering of washable material having the external appearance of said animal's coat and completely enveloping and closely conforming to the shape of said body portion, said outer 110 covering being formed with the appendages for completing the natural appearance of

said animal, and also provided with detachable devices for being removably secured around said body portion.

3. A toy animal comprising an inner incomplete body portion designed to give substantial shape to said animal but free from such appendages as the ears, feet and tail, an outer covering of washable material having the external appearance of said animal's coat and completely enveloping and closely conforming to the shape of said body portion, said outer covering being formed with

the ears, feet and tail of said animal for completing its natural appearance, and also provided with detachable devices for being removably secured around said body portion. 15

Signed at New York, New York, this 3rd day of March, 1911.

HELEN F. TROWBRIDGE.
